CHAIR BED

Fred E. Moore, Alhambra, Calif.

Application April 2, 1928, Serial No. 266,662

1 Claim. (Cl. 155—45)

My invention relates to chairs more particularly a chair capable of production as an article of manufacture distinctively and accurately representative of period designs adapted for manufacture yet embodying the means of facile conversion as a chair bed or lounge effecting the essential features of such articles as a couch or a bed: a comfortable, full length, resilient cushion structure.

10 The objects of my invention are, first, to provide an ensemble structure representative of the more elegant types of furniture which, when utilized as a chair, presents the appearance of a period standard design; second, to provide a 15 structure wherein, utilized as a chair or couch, the cushion members are self contained and readily adjustable for either purpose; third, to provide a structure, adaptable as a chair or a couch, wherein the means devised to function 20 and evolve the latter do not materially increase the cost of production of the adopted design of the former which is in this respect an improvement on a similar article patented by me July 5, 1927, No. 1,634,551.

25 With the above mentioned and other objects in view, the invention consists in the novel construction and combination of parts hereinafter described, illustrated in the accompanying drawings, and set forth in the claim hereunto appended, it being understood that various changes 30 of form, proportion, size and minor details of construction within the scope of the claim may be resorted to without departing from or sacrificing any of the advantages of the invention.

35 Referring to the drawings:

Fig. 1 is a side elevation of the device depicting relative relation of members when functioning as a chair.

Fig. 2 is a side elevation of the device depicting the disposition relation of members when functioning as a couch.

Fig. 3 is a fragmentary perspective of the stop members for securing the swing-back of the device in desired positions.

45 Fig. 4 is a plan view of the extension stool member showing securing and manual movement extension limit means.

Fig. 5 is a plan view section on line 5—5 of Fig. 7 showing the main frame.

50 Fig. 6 is a section on line 6—6 of Fig. 7 showing longitudinal and transverse extension alignment stops for stool.

Fig. 7 is a section on line 7—7 of Fig. 5 showing the lower portion of the main frame and the 55 combined extended position of the stool.

Fig. 8 is an enlarged detail of the member securing the swing-back stop members to the back frame proper.

Fig. 9 is a fragmentary elevational view depicting a modified form: a disappearing drop leg or strut and a main frame structure resting directly on the floor dispensing with the use of legs.

Fig. 10 is a fragmentary detail depicting a modified form of support for the "front" of 10 main frame.

Referring to the drawings in detail, the device comprises a main frame A, a swing-back B, an extension or extensible stool member C, and a unit filler or cushion member D.

The main frame A consists in part of two substantially rectangular integral side frames each composed of a bottom rail 1, an arm 2 and 2', a back post 3 and a knee or brace 4, the several members of each side frame being united 20 by suitable means as dowels and glue. The two integral side frames, finished or upholstered as desired, are united and maintained in relatively fixed upright, spaced, (as desired) relation by means of a spreader 5 and a spreader sill 6 25 the extremities of each sill rigidly secured to, and securing, by suitable means as screws or other means, the two side frames. Resilient closure of the bottom of the main frame A, Fig. 5, effecting support of the unit filler D, when 30 the device is utilized as a couch or bed, is obtained by means of the plain woven webbing or elastic webbing strips 7 the ends thereof secured, by suitable means as tacks, to the under side of the bottom rails 1 and top face of the 35 spreader 5 and spreader sill 6.

The swing-back B consists of a substantially rectangular frame 8 of desired form finished or upholstered in the usual manner requiring no further description. In the design of swing-back B, depicted, the lower portion 9 of the frame 8, with upholstery affixed, is constructed to fit between the back posts 3 of the main frame A. The upper portion 10 of the swing-back B is widened to overlap the upper extremity of the back post 3 and the junction of the arm 2' and form a flush or extended finish of the chair back relative to the main frame A. Closure of the rear plane of the frame 8 is effected in the usual manner as by the use of a sheet of fiber or similar material 11 secured, to form the desired contour, by suitable means as tacking to the frame 8. The lower extremity of the swing-back B is secured to the spreader 5 by a pair of hinges 55

12, upon which, the swing-back is fulcrumed to the desired position as indicated by the dotted line positions *x* and *y* and full line position *z* of Fig. 2. For securing or stopping the swing-back 5 B in any one of the positions designated *x*, *y* and *z*, a position stop member ensemble E (Fig. 3) interactive between the swing-back B and main frame A, is provided.

The position stop member E comprises a transverse bar 13 of sufficient length to allow the adjustable, later described, bearing plates 14, in hole 15 of which the transverse bar 13 is freely rotatable, and the arms 16, rigidly secured to the bar 13, to closely embrace the lower portion 15 9 of the swing-back B and function between it and the adjacent portions of members 1, 3, and 4 forming the side frames of the main frame A. The arms 16 are provided with a slot 17 provided with the notches 18 adapted to engage 20 a fixed stop 19. The fixed stops 19 each consist of a plate 20, Fig. 7, secured to the back posts 3 by the screws or bolts 21. The stop proper consists of a T head struck up from the body of a plate 20, the neck thereof adapted to a sliding fit in the slot 17 of the arms 16 and engageable with the notches 18. The cross bar of the T head proportionally wider than the slot 18 forms a guide maintaining engagement of the parts. To secure reliable engagement of the 30 notches 18 with the stops 19 a tension spring 22 is tensionally positioned and secured between a crank 23, integral with the bar 13, and the frame 8. The relative position of parts and spring tension functioning to maintain any of the several notches 18 of each arm 16 in engagement with the fixed stops 19. A lift 24 is provided for the purpose of releasing engagement of any of the several pairs of notches 18 from the fixed 35 stops 19 thus permitting the swing-back B to be swung, by manual operation, to any and all positions, such as those depicted and designated as *x*, *y* and *z*. The lift 24 consists of a rod bent to form an eye 25 engaging the crank 23 and extending therefrom to a position relatively near 40 the top at the back of the swing-back B, and is there bent at an angle to form a hand hold 26 projecting through the chair back and ornamented as desired. It is evident that an outward lift of the hand hold 26 disengages the stop ensemble E from the fixed stops 19 whereupon 45 the swing-back B may be positioned as desired and the stop ensemble E re-engage with the fixed stops 19, by releasing the hand hold 26.

The pertinent value of adjustability of the stop ensemble E secured, by means of the adjustable bearing plates 14, to the swing-back B and required to coincidently engage the fixed stops 19 secured to the main frame A resides in the fact that in a structure of this character the relation of parts not fixedly integral are not always true in alignment. Any misalignment of the frame 8, secured by the hinges 12 to spreader 5, relative to the main frame A and fixed stops 19 engageable by the stop ensemble E is readily overcome by the adjustable bearing plates 14. The bearing plates 14 are attached to the arms 16 which are previously engaged with fixed stops 19 before fixed attachment of the plates 14 to the frame 8 by suitable means as bolts 27. As 50 the fixed stops 19 are more readily visible, shifting the position of either, to accomodate misalignment of parts, would be detrimental to appearance, whereas the relative position of the bearing plates 14 are hidden from view by upholstery. 55

In the preferred form the back posts 3, extended, form the back legs 28 and the "hidden" supplemental front legs 29 are provided to support the main frame A. The legs 29 consist, as depicted, of iron bent to a right angle and secured by bolts 30 to the spreader sill 6. The lower extremity of the leg 29 being sheathed, as by a rubber socket 31, to protect the surface sustaining the legs. 60

The extension member C is termed a stool as 10 designative of a twofold utilization: a seat and a support for the feet or lower limbs of the occupant. The stool C consists of a unit frame 32, of suitable material as wood, upholstered as desired requiring no further description. The ensemble stool C is adapted, in width to slide between the bottom rails 1 and function on the slide-stop rails 33 fixedly secured, by suitable means as nails, to the inner bottom edge of the bottom rails 1. The slide-stop rails 33 extend 15 from a position at the front of the main frame A, as depicted flush with the end of the bottom rail 1 representative of the extreme withdrawal extension of the rear side 34 of the stool frame 32, to a position just short of that occupied by 20 the rear side 34 when the stool C is in the closed position. The inner ends of the slide-stop rails 33 are provided with a beveled end 35 the front ends 36 being square. As will appear the slide-stop rails 33 form a means performing three pertinent functions relative to the stool C: that of a slide support and two position stops, and in addition afford a maximum area of the webbing closure of the bottom of the main frame A to function in resilient support of the unit filler 35 member or cushion D when the device is utilized as a couch. For further maintaining the stool C in position when in the extended position the alignment stops 37 and 38 are provided, which, as depicted, consist of cleats secured, by suitable 40 means as nails, to the upper surface of the spreader sill 6. The stool frame unit 32 is provided with a pair of legs 39 affixed thereto to project sidewise, as at 39', and be flush with the sides of the main frame arm members 2 to form a pleasing finish of the relative parts. The legs 39 being routed out on the inner side to form a pocket 39' whereby the legs 39, when the stool C occupies the closed or chair proper position, conceal the supplemental legs 29. It will be 45 noted that the main frame A is supported by the integral legs 28 and 29 and that the stool C in extended position, Figs. 2 and 7, is sustained by the spreader sill 6 and legs 39. 50

To the lower edge of the rear side 34 of the 55 stool frame 32 is secured, by suitable means as nails, an engagement lug 40, that depicted consisting of a strip of wood extending from side to side of the stool frame 32 and provided with a notch 41 adapted to engage the alignment stop 38, Fig. 6, when the stool C is in extended position. As will be noted the stool ensemble C is secured to main frame A by means of the manual movement limit stops 42 permitting manual extension of the stool C to the normal 60 position for proper register of the engagement lug 40 with the alignment stops 37 and 38. The limit stops 42 consist of pliable material as webbing secured by suitable means as tacks. The ends of the limit stops 42 being respectively secured to the bottom of the rear side 34 of the stool C and to the top of the spreader 5 of the main frame A. To insure the neat and positive double fold stowing 43, Fig. 1 of the pliable limit stops 42, in the closed position of the stool C, 70 75

they are secured to the bottom closure webbing 7 by tying or knotting 44.

The interactive functions of the engagement lug 40 relative to the slide-stop rails 33 and alignment stops 37 and 38 act as follows, Figs. 1, 2, 6 and 7: In the closed position of the stool C, Fig. 2 and the dotted line position in Fig. 7, the engagement lug 40 is positioned back of the bevel ends 35, thus any tendency of the stool C, 10 during occupancy of the chair, to slide forward toward extension position is counteracted by the bevel ends 35; as the engagement lug 40, to permit forward movement, must rise against the load imposed by the weight of the occupant. 15 Not loaded the stool C is readily drawn outward or extended manually, the engagement lug 40, with but slight obstruction, sliding upward on the bevel ends 35 to slide freely on the slide-stop rails 33. With the stool C extended the engagement lug 40 drops into a position forward or in front of the squared ends 36 or between the squared ends 36 and alignment stop 37. When 20 in this position the engagement lug 40 by impinging on these stop members prevents any longitudinal misalignment of the stool C with relation to the main frame A. Lateral displacement of the stool C in extended position is counteracted by the notch 41 of the engagement lug 40 registering straddlewise of the stop 38 Fig. 6. 25 A unit filler or cushion member D, of desired structure and upholstery, performs the dual function of forming a second-deck seat member or a filler, manually positioned or placed in either instance. In the ensemble device utilized 30 as a chair proper, the unit filler functions as a second-deck of the stool C forming an adjunct of comfort. Used as a "lounge" with the stool C extended and the swing-back in either of the positions indicated by x and y, Fig. 2, the unit 35 filler occupies the space between the swing-back B and extended stool C and rests upon the bottom closure webbing 7 of the main frame A, 40

thereby providing a comfortable ensemble structure for occupancy as a lounge. With the unit filler D in position described as supplementally forming a lounge, simply lowering the swing-back B to the last position, indicated by z Fig. 2, 5 forms a comfortable structure utilizable as a couch or bed. Operation of the device is self evident from the description of the interaction of the several parts.

In the modified form shown in Fig. 9, the 10 drop-legs or struts 45, of thin metal, are mounted freely rotatable on each end of the bar 13 and are positioned and adapted to function between the lower portion 9 of the swing-back B and the arms 16. In the closed position, indicated by the dotted lines of Fig. 9, the drop-leg 45 is swung to a disappearing position 15 between the lower portion 9 of the swing-back B and the side frames of the main frame A. As depicted in Fig. 9, the bottom rails 1 are adapted 20 to rest directly on the floor as at 46.

In the modified form shown in Fig. 10, the hidden legs 29 are omitted and the visible turned legs 47 are substituted and secured, by suitable means as dowels 48, to the spreader sill 6. 25

I claim:

In a chair, a main seat frame, said seat frame forming a seat support, an auxiliary frame arranged to be disposed over the seat support, as well as to form an extension to the main seat 30 frame for a leg rest, said auxiliary frame having front supporting legs, and a pair of flexible fabric members for limiting the extension movement of the auxiliary frame, one end of each of said members being fastened to the main seat 35 frame near the side edge of the frame, and the other end being fastened near the rear edge of the auxiliary frame to the under side thereof, whereby when the auxiliary frame is disposed in the seat frame, said flexible members are in 40 doubled relation between the two frames.

FRED E. MOORE.
